UNITED STATES PATENT OFFICE.

CHARLES S. BIRD, OF EAST WALPOLE, MASSACHUSETTS, ASSIGNOR TO BIRD MACHINE COMPANY, A CORPORATION OF MASSACHUSETTS.

ROTARY SCREEN FOR PAPER-STOCK.

1,304,253.

Specification of Letters Patent. Patented May 20, 1919.

Application filed September 16, 1918. Serial No. 254,308.

To all whom it may concern:

Be it known that I, CHARLES S. BIRD, a citizen of the United States, residing at East Walpole, in the county of Norfolk and 5 State of Massachusetts, have invented certain new and useful Improvements in Rotary Screens for Paper-Stock, of which the following is a specification.

This invention pertains to an improved 10 rotary screen for paper stock.

The invention has for its main object, the production of a screen that will insure a constant output of stock, and which by reason of its peculiar construction will require but a minimum of power to operate 15 it, and at the same time is durable and consequently of long life.

A still further object is to provide means working in conjunction with the usual water 20 cleaning jet or spray to remove strings and snags from the screen surface.

The screen is of the inflow type where- 25 in the screen proper is immersed in a vibrating vat and the screened stock discharged outwardly through the open head or end of the screen.

The machine is shown in the annexed drawings, wherein:

Figure 1 is an end elevation of the head or 30 driving end of the machine;

Fig. 2 a transverse vertical sectional view, and

Fig. 3 a longitudinal vertical sectional view.

In the drawings, 1 denotes a suitable 35 frame or standard at the head end and 2 a standard or frame at the opposite end. The screening cylinder proper may be of any approved form and in that illustrated 40 comprises a closed head 3, an open ring-shaped head 4 between which extend suitable tie rods 5, and screen supporting and attaching bars 6. The screening surface is preferably formed of segmental perforated 45 plates 7 produced from phosphor-bronze or the like, which are attached by screws to the heads and bars.

Head 3 has fixedly secured thereto a stub shaft 8 which extends outwardly through 50 a stuffing box 9 mounted in standard 1. Said shaft has secured to it a gear 10 and derives its motion at a reduced speed, through the gearing as shown, from a band wheel 11. Head 4, which is of ring form, 55 extends through and is supported at its

outer end by suitable bearing blocks 12 preferably produced from lignum-vitæ held in place in the standard 2 by a ring or collar 13. A discharge mouth 14 is secured to standard 2, and the screened pulp passes 60 therefrom into a discharge box (not shown) which is connected to the head box of the paper machine.

The vat of the machine is designated by 15 and is sustained in yoke-shaped frames 65 16 and 17 which latter at one side are supported by laminated spring members 18, the opposite side being pivotally supported from links 19, the pivots for the upper ends of which are sustained by standards 20. A 70 radius bar 21 is connected to one of the lower link pins and a pitman 22 is adjustably secured thereto, the opposite end of the pitman coacting with an eccentric 75 23 carried by a driven shaft 24. Through this arrangement the tank or vat is vibrated, the amplitude of vibration being regulated and determined by adjustment of the pitman with reference to the radius bar or 80 arm 21.

A flexible connection is effected between each end of the vat and the adjacent standards 1 and 2 which, in effect, form heads or ends for the vat. I have found that strips or bands of rubber, denoted by 25, 85 26 Fig. 3, form an effective simple and durable connection and are preferably held in place by metallic straps 26 overlying the bands and secured in place by screws passing into the vat body and into flanges 27 90 95 formed on the respective standards.

The vat at its lower side is provided with a drain 28 into which settle the impurities that are held back by the screen, down-coming unscreened stock assisting gravity 95 in this action. The impurities thus caught are removed in a small constant stream to a small auxiliary screen (not shown), where any good stuff is removed and re-turned to the flow-box 29 which discharges 100 into the vat, Fig. 2.

Projecting through the head 4 and ex- 105 tending throughout the length of the screen in the upper portion thereof is a trough or tray 30, and located above said tray and within the screen is a spray pipe 31. The water forced from said pipe passes through the screen and acts to dislodge any matter which is held in the screen openings or perforations, the jet carrying such ma- 110

terial upward and impinging against a deflector 32 of a pan 33. Pipes 34 extending from the pan discharge the water and the removed material into the tray 30, which latter also catches the water which splashes back from the spray.

It has been found that the spray will not remove all strings and snags from the screen surface, and as such substances tend to clog the screen, I employ a rotary wiper or beater to effect such removal before the then exposed portion of the screen surface is again submerged. Supported in suitable bearings on the standards 1 and 2 is a shaft 35 to 10 which is imparted a rapid rotation. Said shaft carries a wiper or beater, the flexible elements 36 whereof contact the screen surface and act to remove any strings, snags or other adhering substances therefrom. Said 15 elements will preferably be formed of felt—though bristles or wires may be employed. Felt, however, is found preferable, as it does not wear away readily and moreover does not wear away the screen.

20 Preferably the screen is rotated slowly in a direction the reverse of that of the wiper, which latter, as above noted, has a relatively high speed. Any material which may pass the screen cleansing jet or spray will therefore be removed by the wiper, such removal being facilitated by the difference in speed of rotation between the screen and wiper. A hood or guard 37 overlies the wiper, and prevents splashing of the water and waste 25 material which is removed thereby.

What is claimed is:

1. In a machine of the character specified, the combination of a vat, means for vibrating the same; a screen mounted for rotation within said vat; means for feeding the stuff to be screened to the vat; and a rotatable beater contacting the outer surface of the screen and acting upon the exposed surface thereof.
2. In a machine of the character specified, the combination of a vat; a screen mounted for rotation within said vat; means for feeding stuff to the vat and exteriorly of the screen, said screen having an inward flow; a jet pipe located within the screen above the stuff level of the vat; a wiper contacting the exposed outer face of the screen after it passes the jet; and means for rotating the wiper at a relatively high speed.
3. In a machine of the character specified, the combination of a vat; a screen mounted for rotation within said vat; means for feeding stuff to the vat and exteriorly of the screen, said screen having an inward flow; a jet pipe located within the screen above the

stuff level of the vat; a flexible wiper contacting the exposed outer face of the screen after it passes the jet; and means for rotating the wiper at a relatively high speed.

4. In a machine of the character specified, 65 the combination of a pair of frames or standards; a vat; a flexible connection between the ends of said vat and frames, said frames forming the heads or ends of the vat; an inflow screen mounted for rotation 70 in the vat; means for vibrating the vat; a spray pipe located interiorly of the screen; and a flexible wiper acting upon the outer surface of the screen beyond the spray pipe.

5. In a machine of the character specified, 75 the combination of a U-shaped vat body; a pair of frames or standards; a flange extending from each frame toward the body; a rubber strip secured to each flange and to the adjacent end of the body and forming a 80 closure between said parts; means for vibrating said body; an inflow screen mounted for rotation within said vat; a spray pipe located interiorly of the screen; and a flexible rotary beater acting on the outer surface 85 of the screen at a point beyond the spray pipe.

6. In a machine of the character specified, the combination of a U-shaped vat body; a 90 pair of frames or standards; a flange extending from each frame toward the body; a rubber strip secured to each flange and to the adjacent end of the body and forming a closure between said parts; means for vibrating said body; a screen mounted for 95 rotation with said vat; and a rotary wiper embodying a series of flexible members adapted to contact the exposed surface of the screen.

7. In a machine of the character specified, 100 the combination of a U-shaped vat body; a pair of frames located adjacent the ends thereof; a flexible connecting closure between the vat ends and the frames; a drain located at the lower side of the vat; means 105 for vibrating the vat transversely to its axis; a screen mounted in said vat, one end of the screen being open and discharging outwardly therefrom; a spray pipe located within the upper part of the screen; and a 110 rotary flexible beater working against the surface of the screen in rear of the spray pipe, said beater rotating in a direction the reverse of that of the screen and having a peripheral speed in excess of that of the 115 screen.

In testimony whereof I have signed my name to this specification.

CHARLES S. BIRD.
